UNITED STATES PATENT OFFICE.

JOHANNES DREWES, OF GIDEON, NETHERLANDS.

PUNCHING-MACHINE.

1,380,542.

Specification of Letters Patent. Patented June 7, 1921.

Application filed November 10, 1919. Serial No. 336,873.

To all whom it may concern:

Be it known that I, JOHANNES DREWES, a subject of the Queen of the Netherlands, residing at Gideon, near Groningen, Netherlands, have invented certain new and useful Improvements in Punching-Machines, of which the following is a specification.

Punching machines have been proposed in which a plurality of punches are mounted 10 in a common reciprocating block. They serve the purpose of punching a complete series of holes at each working stroke of the machine.

The main object of my present invention 15 is to make said machines suitable for perforating plates in which the numbers of holes in successive series are unequal. With this and other objects in view I connect one or a plurality of punches, or punch holders, pivotally with the said block, preferably so as to adapt them to turn in a plane 20 at right angles to the axis of the row of punches, and I associate said punches, or punch holders, with means by which they 25 may be swung out and thereby rendered inoperative.

Other features of my present invention 30 will be described with reference to the annexed drawing and more particularly pointed out in the claims.

In the drawing:

Figure 1 is a front elevational view of a machine constructed in accordance with my new principles, some of its parts being 35 omitted;

Fig. 2 is a sectional view along line A—A in Fig. 1, and

Fig. 3 illustrates part of a ship's plate as 40 may be perforated semi-automatically by a machine shown in Figs. 1 and 2 and provided with a suitable number of punches.

The illustrated machine comprises two supports 1 and 2 for the main shaft 3 which carries a loose gear 4. The said gear meshes 45 with a pinion 5 on a shaft 6 provided with a pulley 7. Secured on shaft 3 is a disk 8 which may be coupled with and released from the gear 4 by means of a mechanism 9, the exact construction of which is of no importance as far as my invention is concerned.

On the shaft 3 are keyed two eccentric disks 10, 10^a having freedom of rotation in

corresponding holes of slides 11 and 11^a, to which reciprocatory horizontal movement 55 may be imparted in recesses of a heavy block 12. The block 12 is vertically movable in suitable guides formed in the supports 1 and 2.

A shaft 13 carried by the block 12 serves 60 for supporting a plurality of punch holders 14 which are mounted side by side and adapted to rotate about shaft 13 within a recess of block 12 in the direction of the arrow shown in Fig. 2. Each punch holder 65 is adapted to receive a punch 15.

Supported in bearings of the block 12 are two horizontal shafts 16 and 17. Each holder 14 is pivotally connected by means of a link 18 with a lever 19 on shaft 16; 70 the pivot connecting the parts 18 and 19 is connected by a link 20 with the end of a lever 21 on shaft 17. The levers 19 and 21 are adapted to be rigidly secured on the shafts 16 and 17 respectively by means of 75 set screws 16^a and 17^b. By releasing these screws the said levers may be uncoupled from said shafts.

Keyed on shaft 16 is a handle *h* coöperating 80 with an arcuate guide piece *c* provided with a slot in which the said handle may be secured, for instance by a clamping screw.

On shaft 17 is secured a lever 22 provided at its end with an antifriction roller 23. A coiled spring 17^a on shaft 17 always tends to 85 press the said roller in a counter clockwise direction against a cam 24. Said cam is keyed on a shaft 25 supported in suitable bearings of the block 12 and carrying a ratchet wheel 26 coöperating with a pawl 27. 90 The pawl 27 is mounted in a frame 28 which is loosely mounted on shaft 25 and pivotally connected by a lever 29 with a shaft 30 supported in bearings of the slides 11 and 11^a. The distance between the pivot connecting lever 29 and frame 28, and shaft 25 may be increased or reduced by means of a screw 31 which is prevented from moving axially in the frame 28 and which coacts 95 with a nut pivoted to the end of lever 29. 100

The work piece *w* is supported by a frame of which only two T-beams 32, 32^a are shown in the drawing. These beams are provided with racks co-acting with pinions 33, 33^a on a shaft 34 which also carries a ratchet wheel 105 35. The said wheel 35 coöperates with a

pawl 36 mounted in a frame 37 which is pivotally connected by a rod 38 to a travel-
 5 ing nut 39 mounted on the latter being rotatable within a block 41 but prevented from
 endwise movement therein. The block 41 is
 secured to a disk 42 on shaft 3; the said disk
 10 42 is provided with a radial slot in which
 the nut 39 is adapted to reciprocate. It will
 be understood that owing to a rotation of
 screw 40 the nut 39 will move radially over
 15 disk 42, whereby the length of stroke of rod
 38 may be varied. The pawls 27 and 36 are
 loosely mounted in their frames 28 and 37,
 and are provided with enlarged upper ends
 20 or heads 27^b and 36^a by means of which they
 may be lifted out of engagement with their
 ratchet wheels. These heads are provided
 on their under faces with depending lugs or
 25 projections 27^c and 36^a adapted to fit in
 diametrically opposite recesses in the
 frames, so that the pawls after having been
 lifted out of engagement with the ratchets,
 30 may be turned through 180° and then re-
 engaged therewith in inoperative position,
 the projections and recesses coacting to hold
 the pawls in either position.

The shaft 34 further carries two rollers
 43, 43^a for supporting the flanges of the
 beams 32, 32^a, and rollers 44, 44^a for support-
 35 ing the work piece *w*.

Mounted on a shaft 45 supported by the
 40 frame of the machine are three bell crank
 levers 46, each of which is provided at one
 end with an antifriction roller 47, its other
 45 end carrying a stud 48 projecting into a
 curved slot in a guide piece 49, whereby the
 lever 46 may be secured so that the roller
 50 47 presses the work piece *w* on the die 50.

The main shaft 3 of the machine carries
 40 two cams 51, 51^a coacting with pins 52,
 52^a which are suitably guided in a vertical
 direction and which are pressed by springs
 against the said cams. The pins 52, 52^a are
 45 tapered at their lower ends. If I wish to
 perforate the work piece *w* in such a man-
 ner that the number of holes in all series is
 the same and corresponds with that of the
 punches in the machine, I may for instance,
 50 secure all levers 21 to the shaft 17 by tight-
 ening their set screws 17^b, and I render
 the pawl 27 inoperative, for instance, by
 turning it through 180° about its longitudi-
 55 nal axis as explained above; at the same
 time I see to it that the cam 24 assumes
 the position shown in Fig. 2, that is a pos-
 60 sition wherein the shaft 17 under the action
 of the coiled spring 17^a holds the punches in
 their operative positions. It will be under-
 stood that under these conditions my
 65 machine operates in quite the same manner as
 the ordinary punching machines having a
 plurality of stationary punches arranged
 side by side.

If during the operation of the machine
 65 a distinct punch or a plurality of distinct

punches should be swung out, I secure the
 levers 19 of those selected punches on the
 shaft 16 by means of the set screws 16^a pro-
 70 vided for this purpose, and I uncouple the
 corresponding levers 21 from shaft 17. As
 long as said punches are to remain operative
 I keep the handle *h* in its lowermost pos-
 75 ition, but as soon as it is desired for the
 said punches to be swung out I turn the han-
 dle *h* and I secure same in its highest pos-
 80 ition relative to the curved slot *c*.

In case it is necessary for selected punches
 to automatically or periodically become op-
 erative and inoperative, I throw the pawl 27
 85 into operative engagement with the ratchet
 wheel 26, whereby the cam 24, owing to the
 horizontal motion of the slides 11, 11^a, is
 periodically turned through a given angu-
 lar distance. As long as the roller 23 en-
 gages the recessed portion of the cam 24,
 90 those punch holders whose lever system 18,
 19, 20, 21 is rigidly secured to shaft 17, re-
 main in their operative positions. If, how-
 ever, the lever 22 is turned by the cam 24
 through a given angular distance in a clock-
 95 wise direction, the said punch holders will
 be swung out and become inoperative.

By means of the screw 40 the distance
 through which the work piece *w* is fed at
 each revolution of shaft 3 may be varied
 95 with a view to the pitch of the series of
 holes. With the aid of screw 31 I may
 control the angular displacement of the cam
 24 per revolution of shaft 3, and conse-
 100 quently the movements of the punch holders
 that are fast on the shaft 17.

If it is desired to vary the pitch of the
 holes in the series, the punch holders 14 are
 simply replaced by a series of holders hav-
 105 ing a corresponding thickness in the direc-
 tion of the axis of the machine.

The pins 52, 52^a have for their purpose to
 hold the work piece in an invariable pos-
 110 ition during the punching stroke, in a man-
 ner well known in the art.

The length of the punches decreases from
 the center of the series toward both ends,
 whereby I realize the advantage that the
 115 punching pressure gradually increases dur-
 ing the working stroke.

What I claim as my invention is:

1. In a punching machine, the combina-
 120 tion of a reciprocatory element; a plurality
 of punching devices pivoted thereto; and
 means for automatically and positively
 swinging a certain selected punching device
 or devices into inoperative position.

2. In a punching machine, the combina-
 125 tion of a reciprocatory element; a plurality
 of punching devices pivoted thereto; and
 means operable automatically at predeter-
 mined regular intervals for positively
 swinging a certain selected punching device
 or devices into inoperative position.

3. In a punching machine, the combina-

- tion of a reciprocatory block formed with a series of sockets; a punch holder pivoted in each socket, each holder being movable independently of all of the other holders into an inoperative position; and means for automatically and positively swinging a selected holder or holders into said position. 5
4. In a punching machine, the combination of a reciprocatory element; operating mechanism therefor; a plurality of punching devices pivoted to said element to move therewith; and means coupled to said operating mechanism for automatically swinging a selected punching device or devices 10 relatively to the reciprocatory element into inoperative position. 15
5. In a punching machine, the combination of a reciprocatory element; a plurality of punching devices pivoted thereto; a rock shaft to which all of the punching devices are individually connectible to swing into inoperative position when said shaft is turned; and means for automatically actuating said shaft. 20
- 25 6. In a punching machine, the combination of a reciprocatory element; a plurality of punching devices pivoted thereto; a rock shaft to which all of the punching devices are individually connectible to swing into inoperative position when said shaft is turned; and means operating automatically at predetermined intervals to actuate said shaft. 30
- 35 7. In a punching machine, the combination of a reciprocatory element; a plurality of punching devices pivoted thereto; a rock shaft to which all of the punching devices are individually connectible to swing into inoperative position when said shaft is turned; operating mechanism for the reciprocatory element; a cam operatively connected with said mechanism; and connections between said cam and said shaft for automatically operating the latter from the 40 former. 45
- 40 8. In a punching machine, the combination of a reciprocatory element; operating mechanism therefor; a plurality of punching devices pivoted to said element to move therewith; means connected to swing a selected punching device or devices relatively to said reciprocatory element into an inoperative position; a cam connected to be driven from said operating mechanism; and connections between said cam and said swinging means for automatically operating the latter from the former. 50 55
- 55 9. In a punching machine, the combination of a reciprocatory element; a plurality of punching devices pivoted thereto; and mechanism for automatically and positively swinging a selected punching device or devices alternately into and out of inoperative position. 60
- 60 10. In a punching machine, the combination of a reciprocatory element; a plurality of punching devices pivoted thereto; and mechanism for automatically and positively swinging a plurality of selected punching devices simultaneously into inoperative position. 70
11. In a punching machine, the combination of a reciprocatory element; a plurality of punching devices pivoted thereto; and mechanism for automatically and positively swinging a plurality of selected punching devices simultaneously first into inoperative position and then back into operative position. 75
12. In a punching machine, the combination of a reciprocatory element; a plurality of punching devices pivoted thereto for swinging movement; an oscillatory shaft disposed parallel with the axis of movement of the punching devices; operating mechanism for the reciprocatory element; a cam connected to be operated by said mechanism; a lever system between said punching devices and said shaft to operate the former from the latter; and a projecting member 80 carried by said shaft for engagement by said cam. 85
13. In a punching machine, the combination of a reciprocatory element; a plurality of punching devices pivoted thereto for swinging movement; a pair of oscillatory shafts disposed parallel with the axis of movement of the punching devices; a lever system between the punching devices and one of the oscillatory shafts; mechanism for 90 automatically operating said reciprocatory element and said lever system; a connection between the other oscillatory shaft and the lever system; and means for manually operating said other oscillatory shaft and 95 holding it in adjusted position. 100
14. A punching machine comprising a reciprocatory carrier; a plurality of punching devices attached to the carrier to move therewith, but capable of movement relative 110 to said carrier into and out of inoperative position; and mechanism for simultaneously moving a plurality of selected punching devices, to the exclusion of the others, into inoperative position. 115
15. A punching machine comprising a reciprocatory carrier; a plurality of punching devices attached to the carrier to move therewith, but capable of movement relative to said carrier into and out of inoperative position; and mechanism periodically moving a plurality of selected punching devices into inoperative position. 120
16. A punching machine comprising a reciprocatory carrier; a plurality of punching devices attached to the carrier to move therewith, but capable of movement relative to said carrier into and out of inoperative position; and mechanism operable automatically to move a plurality of se- 125
- 130

lected punching devices, at predetermined regular intervals, first into inoperative position and then into operative position.

17. A punching machine comprising a reciprocating carrier; a plurality of punching devices attached to the carrier to move therewith, but capable of movement relative to said carrier into and out of inoperative po-

sition; and mechanism operable automatically and simultaneously upon a plurality ¹⁰ of selected punching devices, to the exclusion of others, to move them first into one of such positions and then into the other position.

In testimony whereof I affix my signature. ¹⁵
JOHANNES DREWES.
